UNITED STATES PATENT OFFICE

CLARENCE C. SHIPP, OF INDIANAPOLIS, INDIANA.

REINFORCING-ROLL FOR STEAM-RADIATOR SHIELDS

1,218,707.

Specification of Letters Patent. Patented Mar. 13, 1917.

Application filed October 30, 1916. Serial No. 128,603.

To all whom it may concern:

Be it known that I, CLARENCE C. SHIPP, a citizen of the United States, residing at Indianapolis, in the county of Marion and State of Indiana, have invented certain new and useful Improvements in Reinforcing-Rolls for Steam-Radiator Shields, of which the following is a specification.

Experience has dictated the desirability in providing a bead or reinforcing roll along the upper side edges of that class of steam radiator shields which are formed of light gage sheet metal, as shown in my former U. S. Letters Patent No. 1,174,626, issued March 7, 1916; the said reinforcing roll being adapted to strengthen and at the same time preserve the symmetry of the shields. In practice, however, it has been found during transit, in shipping shields to the places of installation, that the reinforcing rolls are frequently dented and crushed, thereby rendering the section or sections of the shields with mutilated roll unfit for use, which results in considerable material and monetary loss. Moreover, the rolls when formed integral with the shield sections occupy considerable space during shipment, so that the number of shields ordinarily shipped in a commercially regulated sized crate is considerably reduced.

The present invention relates to improvements in reinforcing rolls for steam radiator shields which are formed independently of the shields *per se*; can be shipped independently of the shields in an especially prepared crate, and can be easily placed in position on the shields at the place where the latter are installed.

The object of the invention consists in the provision of a reinforcing roll for steam radiator shields which not only reinforces and strengthens the upper portion of the shield, but adds to the appearance of the shield by removing the bends that inherently occur in metal sheets of considerable area or length.

A further object of the invention consists in the provision of a removable reinforcing roll of the above character which is simple in construction, cheap to manufacture and which adds to the general appearance of the shield.

I accomplish the above objects of the invention, and such others as may appear from a perusal of the specification and claims, by means of the construction illus-

trated in the accompanying drawings, forming a part hereof, in which—

Figure 1 is a fragmentary detail perspective view of the upper end of a steam radiator shield, showing my detachable reinforcing roll in operative position. Fig. 2 is a fragmentary detail cross sectional view, showing the free edge of the roll bearing against the raw edge of the shield. Fig. 3 is a fragmentary detail in plan view of the upper edge of a portion of the shield, showing the irregular curves in the raw edge of the shield, the strip and roll being omitted. Fig. 4 is a fragmentary detail perspective view of the strip and its reinforcing roll, in which the shield is omitted.

Referring to the drawings, 10 and 11 represent two sections which, when assembled, inclose the sides and ends of the steam radiator (not shown) and form the shield unit. Members 10 and 11 are composed of thin sheet metal, and when fabricated into a radiator shield form a frail structure which is easily distorted under strains, while the yieldable surface areas of the members assume irregular curves which mar that even and desirable symmetry a shield unit should present to the eye. To reinforce and preserve the symmetry of the shield, by removing the irregular curves from the surfaces of members 10 and 11, I provide means comprising the metal strips 12 having one edge turned into a reinforcing roll 14. Strips 12 are arranged to bear against the inner sides and along the upper edges of members 10 and 11, and when placed into position the strips are depressed until the upper raw edges of members 10 and 11 are forced between the sides of strips 12 and the free yielding edges 13 of rolls 14, the resiliency of the rolls exerting a constant pressure against the edges of said members.

The cylindrical formation of the rolls 14 adds stability and rigidity to the shield structure, while the resilient free edges 13 of rolls 14 press the upper edges of members 10 and 11 tightly against the sides of strips 12, thus straightening the sides of said members. Hence, strips 12 and rolls 14 add stability and rigidity to the shield unit, and through the straightening of the undulate surfaces of members 10 and 11 the general appearance of the shield unit is materially improved. Strips 12 are secured and held in proper position on members 10 and 11 by means of suitable bolts 15.

From the above description, it will be observed that strips 12 and rolls 14 not only impart all of the advantages to members 10 and 11 which are possible to obtain with integrally formed rolls, but additional advantages are obvious, namely, first, the strips and rolls can be manufactured independently of the members 10 and 11; can be shipped separately and securely, thus obviating possible damage to the rolls, and, second, the strips and rolls can be manufactured from scrap material, a residue which obtains where large sheets of metal are cut in the manufacture of the classes of articles to which members 10 and 11 relate.

Having thus fully described my said invention, what I desire to secure by Letters Patent, is—

1. The combination, with a steam radiator shield, of a shield reinforcing means comprising an independently formed strip of

sheet material arranged along the upper edges of the shield and having its free portion rolled to form a reinforcing roll in which the free resilient edge of the roll bears and exerts pressure against the edges of the shield.

2. The combination, with a steam radiator shield, of a shield reinforcing means comprising an independently formed strip of sheet material arranged along the upper edges of the shield and having its free portion rolled to form a reinforcing roll in which the free resilient edge of the roll bears and exerts pressure against the edges of the shield, and means for securing said reinforcing roll in operative position on said shield.

In witness whereof, I, have hereunto set my hand and seal at Indianapolis, Indiana, this 17th day of October, A. D. one thousand nine hundred and sixteen.

CLARENCE C. SHIPP. [L. S.]
